UNITED STATES PATENT OFFICE.

WALTER RUSSEL MORSON, OF MONTREAL, CANADA.

SEALING DEVICE FOR SEPARATED SHEETS ARRANGED IN A PILE.

SPECIFICATION forming part of Letters Patent No. 772,626, dated October 18, 1904.

Application filed March 11, 1904. Serial No. 197,670. (No model.)

To all whom it may concern.

Be it known that I, WALTER RUSSEL MORSON, a subject of the King of Great Britain, residing at Montreal, in the district of Montreal, in the Province of Quebec, Canada, have invented certain new and useful Improvements in Sealing Devices for Separated Sheets Arranged in a Pile, of which the following is a specification.

10 My invention relates to improvements in sealing devices for separated sheets arranged in a pile, and the object of the invention is to devise a means of holding bills or securities together in bundles in order that none of the 15 said bills or securities may be removed during transport or passage from one person to another without breaking the seal, and thus facilitate the operation of the routine in banks and such corporations and lessen the labor 20 and risk incident to the handling of valuable packages of moneys or securities; and it consists, essentially, of a clamp having stationary sides and removable parts in which the bills or securities are held, means for securing said 25 parts in position, and an envelop inclosing the clamp and ends of said bills or securities, the various parts being constructed and arranged in detail, as hereinafter more particularly described.

30 Figure 1 is a perspective view of a bundle of bank-bills held between the removable parts of the clamp in the press. Fig. 1^a is a perspective view of the clamp to engage said removable parts. Fig. 2 is a perspective view of a bundle of bank-bills clamped and 35 inclosed in the envelop and sealed. Fig. 3 is a view showing a side elevation of the clamped bank-bills. Fig. 4 is a perspective detail of the envelop. Fig. 5 is a perspective detail 40 showing the removable parts of the clamp.

Like letters of reference indicate corresponding parts in each figure.

45 *a* is the clamp, having the backbone *b* and the parallelly-arranged pairs of fingers *c* extending therefrom.

d represents plates forming the removable parts of the clamp *a* and coacting with the fingers *c*.

50 *e* is a press of any suitable pattern as regards the means of operation.

f represents bosses on the ram *g* of the press.

h represents bosses directly under the bosses *f* and on the bed-plate *i*.

j is a spring secured to the ram *g*, at the 55 outer side thereof and extending slightly below.

k represents pins projecting from the bed-plate *i* at each side thereof.

l is an envelop open at all sides, having the 60 extending flaps *m* and the inwardly-folding portion *n*.

o is a bundle of bank-bills held in the clamp *a* and inclosed in the envelop *l*.

p is a seal affixed over the flaps *m* and holding the same together and to the envelop proper.

This device is more particularly applicable to bundles of bank-bills, though other securities may be held therein, as the clamp and 70 envelop may be made of any desired size, as also the press for securing the clamp in position.

The operation of the device may be readily understood from the detailed description here- 75 tofore and the accompanying illustrations, though to be more explicit I shall explain the device as applied to bank routine.

It is customary for banks frequently to pay out money in large amounts or to exchange 80 money in large amounts between themselves, and for convenience sake the general practice is to divide the total amount, so that it may be made up of several parts arranged in bundles. These bundles usually comprise 85 piles of one hundred bills of the various denominations, and in paying out each of the bundles requires to be counted by the payee, and in making exchanges between themselves or through clearances the bundles are sent 90 to each end.

In my device the risk of the transfer of bundles of bills from one person to another is eliminated, as the number of bills in the 95 bundle can be counted with great facility before the seal is broken—that is to say, the sealed part of the bundle is entirely at one end.

In sealing the bundle the plates or remov- 100

able parts are placed one between the spring and a pin on the inner side of the ram of the press, the said spring holding it in position over the bosses, and the other is placed between the pins projecting from the bed-plate, also over the bosses. The end of the pile is inserted between the plates in such a way as to leave the latter extending beyond the edges at each side of the pile. The ram is then 5 brought down by a suitable lever or wheel, bringing the plates close together and compressing the bills therebetween. The fingers of the clamp are then inserted between the bosses and other guiding parts of the ram 10 and bed-plate until the backbone of the clamp reaches the edge of the plates and the compressed bills. The pressure is then relieved and the bills remain securely clamped between the plates, being held in that position 15 by the fingers of the said clamp. The clamped bills are then placed in the envelop and the inwardly-folding portion folded over and the flaps brought around the bundle of bills inside of the extending ends of the plates and a 20 suitable seal affixed to hold the said flaps together and to the inwardly-folding portion. The bills are now secure from being tampered with.

30 The envelop may be made of any suitable material, but preferably of a strong paper or linen-lined paper, as such will withstand the rough usage attending the handling of bundles of bills.

35 The plates or removable parts of the clamp are also preferably lined with cloth or other material in order to still more securely hold the bills.

What I claim as my invention is—

1. A sealing device for a plurality of separated sheets arranged in a pile comprising a clamp having stationary sides in which said pile is secured, and an envelop inclosing the clamp and the end of said pile, as and for the purpose specified.
- 40 2. A sealing device for a plurality of separated sheets arranged in a pile comprising a clamp having a backbone, and pairs of fingers

extending from the edges thereof parallelly arranged respectively in which the separated sheets are held, and an envelop inclosing said 50 clamp and the end of said pile, as and for the purpose specified.

3. A sealing device for a plurality of separated sheets arranged in a pile comprising a clamp having a backbone, and pairs of fingers 55 extending from the edges thereof parallelly arranged respectively, a pair of plates between which the said separated sheets are held in the clamp, and an envelop inclosing said clamp and the end of said pile, as and for the 60 purpose specified.

4. A sealing device for a plurality of separated sheets arranged in a pile comprising a clamp having a backbone, and pairs of fingers 65 parallelly arranged respectively, and plates between which the ends of said sheets are held, and means for securing said separated sheets between said plates and fingers, as and for the purpose specified.

5. A sealing device for a plurality of separated sheets arranged in a pile, in combination, a clamp having removable parts and securing the end of said pile, and having said removable parts extending beyond the edges thereof, an envelop having open sides and 70 flaps surrounding said pile inwardly of the said extending removable parts, and a seal affixing said removable parts to the other portion of the envelop, as and for the purpose specified.

6. In a device of the class described, an envelop comprising a flexible straightaway portion, and strips extending laterally from the said straightaway portion at one end and forming the closing-flaps of the envelop, as 75 and for the purpose specified.

Signed at Montreal, in the district of Montreal, in the Province of Quebec, Canada, this 9th day of March, 1904.

WALTER RUSSEL MORSON.
